UNITED STATES PATENT OFFICE.

LOUIS MOESLEIN, OF NEW YORK, N. Y.

DESIGN FOR ORNAMENTAL MATS.

Specification forming part of Design No. 7,004, dated November 25, 1873; application filed August 21, 1873.
[Term of Patent 7 years.]

To all whom it may concern:

Be it known that I, LOUIS MOESLEIN, of the city, county, and State of New York, have invented a new and original Design for Ornamental Mats; and I do hereby declare the following to be a full, clear, and exact description thereof, which will enable those skilled in the art to make and use the same, reference being had to the accompanying drawing forming a part of this specification, in which drawing—

Figure 1 represents a face view of my design. Fig. 2 is a central section of the same.

Similar letters indicate corresponding parts.

This invention consists in the design for a mat of a circular center surrounded by the stamens and petals of a rose, and by a border of foliage and flowers, arranged in such a manner that a very beautiful effect is produced.

In the accompanying illustration of this invention, *a* designates the center of my mat, and *b* designates the stamens and petals,

which, together with the center *a*, form a "moss-rose" in bloom. This is surrounded by a series of leaves, *c*, and roses *c**, which form an ornamental border. The roses *c** grow out from under the leaves *c*, imparting to the whole a novel appearance, and a stem, *d*, extends from beneath the central rose, whereby the effect of the whole is still further improved.

What I claim as new, and desire to secure by Letters Patent, is—

1. The design for a mat, having the leaves *c*, roses *c**, center *a*, and stem *d*, as herein shown and described.

2. The design for a mat, the same being formed with the leaves *c*, roses *c**, stamens and petals *b*, and center *a*, as herein shown and described.

LOUIS MOESLEIN.
